METHOD OF INTRODUCING MERCURY INTO
ELECTRIC DISCHARGE LAMPSBasil Noel Clack, Wembley Park, England, as-
signor to General Electric Company, a corpora-
tion of New YorkNo Drawing. Application May 8, 1948, Serial No.
25,998. In Great Britain July 17, 1947

2 Claims. (Cl. 316—21)

1
My invention relates to metal vapor electric discharge devices of the kind used as lamps for illumination purposes.

When a metal, such for example as mercury, has to be introduced into the envelope of a device of the kind referred to, it is usually either distilled into the envelope after the device has been baked, or tipped in from a side tube after the device has been sealed off the exhaust pump.

Both of these methods are usually satisfactory 10 for bench pumping but, if automatic pumping is required, neither is easy to apply. In particular, distillation is not practicable when automatic pumping is carried out, as is usual, through a rubber connection.

It is not possible to put the mercury into the envelope before placing the envelope on the pump because normal baking temperatures (in the region of 400° C.) cause it to distill away.

It is an object of this invention to provide a method, alternative to those above referred to, for introducing mercury into the envelope of a discharge device of the kind referred to, this method being of particular value when automatic pumping is employed. Other objects and advantages of my invention will appear from the following description.

According to the present invention a method of manufacturing a mercury vapor electric discharge device of the kind set forth comprises the steps of introducing into the envelope of the device a compound of mercury, the compound being one which does not decompose to yield the mercury at the baking temperature but which can be decomposed to yield the mercury at a higher temperature, baking and pumping the device, allowing the device to cool to a temperature at which the said mercury condenses, locally heating the said compound to decompose it and thus produce the said mercury, pumping off any undesired gaseous product of the decomposition, and sealing off the envelope. Any other gases which may be required in the envelope can, of course, be introduced before the sealing off.

More particularly, the process may be carried out as follows:

A small quantity, for example, a few milligrams, of mercuric oxide is placed either on an electrode or electrode support or on a metal disc specially provided for the purpose within the envelope of a discharge device. The device is then baked at a temperature of about 400° C. and pumped. At this temperature the mercuric oxide does not decompose. The device is then allowed to cool to a temperature at which mercury condenses and local heating of the mercuric oxide is then carried out; for example, by eddy-current heating or positive ion bombardment to

raise the temperature of the mercuric oxide to 800–1000° C. The mercury so liberated condenses on the walls of the envelope instead of being distilled away as would be the case if the decomposition of the mercuric oxide took place at a higher temperature. The oxygen liberated by the decomposition is pumped off, any gas-filling required is carried out and the envelope is sealed off the pump.

5 A binder may be used to cause the mercuric oxide to adhere to the electrode or other support. In the case of mercuric oxide an organic binder should not be used as these have been found to act as reducing agents and cause decomposition at a lower temperature than is desired. Suitable

binders are potassium silicate or phosphoric acid. A binder may be rendered unnecessary by arranging the mercuric oxide in a box which is sufficiently closed to retain the oxide but allows 15 the products of decomposition to escape. A suitable box may be of nickel formed in two flanged halves, the flanges being spot-welded together, thus leaving crevices through which the products of decomposition can escape.

20 The invention is not limited to the use of mercuric oxide. Any other mercury compound which fulfills the requirements set forth may be used.

What I claim as new and desire to secure by Letters Patent of the United States is:

30 1. The method of manufacturing a mercury vapor electric discharge lamp which comprises the steps of introducing into the envelope of the lamp a compound of mercury which does not decompose to yield the mercury at the lamp-baking 35 temperature but which can be decomposed to yield the mercury at a higher temperature, baking and exhausting the lamp, after the lamp has cooled to a temperature at which mercury condenses locally heating the compound to decompose it, evacuating any undesired gaseous product of the decomposition, and subsequently sealing off the envelope.

40 2. The method of manufacturing a mercury vapor electric discharge lamp which comprises the steps of introducing a quantity of mercuric oxide into the envelope of the lamp, baking the lamp at a temperature of the order of 400° C. and exhausting it, after the lamp has cooled to a 45 temperature at which mercury condenses locally heating the mercuric oxide to decompose it and condense it in the walls of the envelope, evacuating the oxygen liberated by the decomposition, and subsequently sealing off the envelope.
